UNITED STATES PATENT OFFICE.

LOUIS RAFFALOVICH, OF NEW YORK, N. Y., ASSIGNOR TO THE S. B. R. SPECIALTY COMPANY, A CORPORATION OF NEW YORK.

MUFFLER CUT-OUT FOR EXPLOSIVE-ENGINES.

942,011.

Specification of Letters Patent. Patented Nov. 30, 1909.

Application filed January 18, 1908. Serial No. 411,467.

To all whom it may concern:

Be it known that I, LOUIS RAFFALOVICH, a citizen of the Republic of France, now residing in the city and State of New York, 5 have invented certain new and useful Improvements in Muffler Cut-Outs for Explosive-Engines, of which the following is a specification.

My invention relates to devices whereby 10 the operator of an explosive engine provided with an exhaust muffler or other sound-deadening means, may at will provide a discharge opening for the exhaust of the engine without causing the same to pass 15 through the muffler.

It is well known that exhaust mufflers such as are commonly used in connection 20 with explosive engines detract considerably from the efficiency of such engines on account of the re-action produced by the restricted escape of the exhaust. It is desirable therefore to provide means by which 25 when all possible power is desired, the muffler may be cut out of action and a free exhaust discharge provided.

My invention seeks to provide simple, efficient and economical means of achieving this result.

The invention consists in the novel construction, arrangement and combination of parts as hereinafter more particularly described.

In the accompanying drawings, Figure 1 is a side view of a portion of the exhaust 35 discharge pipe of an explosive engine, showing my invention applied thereto, the latter being shown in section; Fig. 2 is a top view of the exhaust pipe, showing a portion of its upper wall above the muffler cut-out 40 broken away so as to look down into the interior of the latter; Fig. 3 is a transverse vertical section through the line 3—3 of Fig. 1, Fig. 4 is a sectional view of the cut-out showing another form of escape valve, and 45 Fig. 5 is a sectional view of a portion of my invention, showing the preferred form of the same. Fig. 6 represents a side view partly in elevation and partly in section of an automobile provided with this improvement.

A represents a portion of the exhaust pipe of an explosive engine, at one end of which the muffler is located. In the lower part 50 of the pipe A an opening is formed, adapted to permit the exhaust from the engine to

pass into the cut-out as hereinafter described. The cut-out is secured to the pipe immediately below this opening. The cut-out comprises an enlarged upper portion B of approximately semi-cylindrical form in end 60 view, constituting a segmental attaching flange adapted to fit on the pipe A. This portion projects longitudinally beyond the main or lower portion of the cut-out, and underneath these two projecting ends are 65 passed the U-shaped supports D D, the upper ends of which are screw-threaded and pass through perforations in the ends of the supporting-pieces E E and are secured by the nuts F F. 70

The lower or main portion of the cut-out comprises an exhaust chamber C having in one wall a valve opening provided with a valve-seat in which when normally closed lies a valve G having a stem H to which the 75 valve is secured by a pin I. This stem slides in a sleeve K fixed to and projecting from the other side of said chamber opposite said valve opening, said sleeve being of sufficient length to steady the stem and cause the valve 80 to always find its seat upon closing. A coiled spring L extends between the pin M in the stem H, and the sleeve K, and serves to keep the valve G normally closed against the pressure of the exhaust, but yields upon 85 being subjected to any unusual or excessive pressure. It will be seen that the device thus also performs the function of a safety valve, yielding in case the pressure of the exhaust becomes too great, and permitting its escape 90 directly without passing through the muffler. The exhaust chamber C on the muffler cut-out is of somewhat larger area than the exhaust pipe A, and the valve opening in said exhaust chamber is preferably of the same 95 or approximately the same area as said exhaust pipe, so there will be no back pressure in the exhaust pipe when the valve of the cut-out is fully open.

In Fig. 4 is shown another form of my invention in which the valve G² is adapted to be drawn inward to allow the escape of the exhaust when it is desired to allow same to escape without passing through the muffler. In this form a coiled spring L² is provided 105 to close the valve again after it has been opened, one end of the spring being hooked into a perforation in a lug N and the other end being secured to the stem H² at the point O. 110

In Fig. 5 is shown a modified method of securing the cut-out to the exhaust pipe. The cut-out is shown provided with lugs P cast integral with the upper part thereof, B, through which and through the supporting pieces Q pass bolts upon which are screwed nuts R.

When it is desired to cut out the muffler of an explosive engine provided with my invention, for the purpose of utilizing the full power of the engine or for any other reason, the valve is opened by the operator, whereupon the exhaust passes into the open air directly through the opening thus caused.

Fig. 6 shows the invention applied to an automobile. The engine exhaust pipe A is there shown connected at one end with the explosive engine 10 and at the other end with a muffler 20. The form of cut-out C there shown corresponds with that shown in Fig. 4 in which the valve opens inward. A cord S is connected at one end to the valve spindle H² and passes over a pulley T and through eyes Y in the dashboard where it may be conveniently reached by the operator. The use of my invention also serves to keep the muffler from becoming clogged by oil and debris of various kinds carried out by the exhaust, as these will tend to drop into the well formed by the cut-out and will be blown out by the exhaust whenever the valve of the cut-out is opened.

It is obvious that various changes in the details of the construction and mode of attachment of my invention may be made without departing from the spirit of the invention.

One of the principal advantages of my invention is the ease with which it may be attached to engines already in use which are not provided with such a muffler cut-out device. All that it is necessary to do in such a case is to provide a suitable opening in the exhaust pipe and my invention clamped thereon in the manner described or in any suitable way.

Having thus described my invention, what I claim as new and desire to secure by Letters Patent is as follows:

1. The combination of an explosive engine exhaust pipe provided with a discharge opening on one side, a muffler connected with said pipe, a muffler cut-out disposed on said exhaust pipe opposite said discharge opening between the engine and the muffler and comprising an exhaust chamber of larger area than said exhaust pipe and provided with an exhaust opening of approximately the same area as said exhaust pipe, a valve for closing said opening, a spring for seating said valve, and means for opening said valve against the tension of said spring.

2. The combination of an explosive engine exhaust pipe provided with a discharge opening, a muffler on said exhaust pipe, and

a muffler cut-out disposed on said exhaust pipe opposite said discharge opening between the engine and the muffler and comprising an exhaust chamber of larger area than said exhaust pipe and provided with an exhaust opening of approximately the same area as said exhaust pipe, a valve for closing said exhaust opening arranged to open inward from its seat, a spring for seating said valve, and means for opening said valve against the tension of said spring.

3. The combination of an explosive engine exhaust pipe provided with a discharge opening, a muffler on said exhaust pipe, and a muffler cut-out disposed on said exhaust pipe opposite said discharge opening between the engine and the muffler and comprising a longitudinal segment adapted to fit against the side of said discharge pipe, and having an opening adapted to register with the side openings in said pipe, and an exhaust chamber dependent from said segment, one wall of said chamber having an exhaust opening and the other wall thereof having a fixed sleeve opposite said opening, a valve spindle adapted to slide in said sleeve, a valve on said spindle adapted to close said exhaust opening, a spring for seating said valve, and means for opening said valve against the tension of said spring.

4. As an article of manufacture a muffler cut-out adapted for attachment to the exhaust pipe of an explosive engine, said muffler cut-out comprising an exhaust chamber provided with an exhaust opening on one side and a fixed sleeve on the other side opposite said opening, a valve stem slideable in said sleeve, a valve attached to said stem and adapted to close said exhaust openings, and a spring for seating said valve, said chamber having a segmental flange adapted to fit such exhaust pipe.

5. As an article of manufacture a muffler cut-out adapted for attachment to the exhaust pipe of an explosive engine, said muffler cut-out comprising an exhaust chamber provided with an exhaust opening on one side and a fixed sleeve on the other side opposite said opening, a valve for closing said exhaust opening secured to said stem and opening inwardly into said chamber.

6. As an article of manufacture a muffler cut-out adapted for attachment to the exhaust pipe of an explosive engine, said muffler cut-out comprising an exhaust chamber provided with an exhaust opening on one side and a fixed sleeve on the other side opposite said opening, a valve stem slideable in said sleeve, a valve attached to said stem and adapted to close said exhaust opening, and a spring for seating said valve, said chamber having a segmental flange adapted to fit such exhaust pipe, and means for securing said segmental flange to said exhaust pipe.

7. As an article of manufacture a muffler cut-out adapted for attachment to the exhaust pipe of an explosive engine, said muffler cut-out comprising an exhaust chamber provided with an exhaust opening on one side and a fixed sleeve on the other side opposite said opening, a valve stem slidable in said sleeve, a valve attached to said stem and adapted to close said exhaust opening, and a spring for seating said valve, said chamber having a segmental flange adapted to fit such exhaust pipe, and U-shaped clamps for fastening the cut-off to such exhaust pipe.
- 15 8. As an article of manufacture a muffler cut-out adapted for attachment to the exhaust pipe of an explosive engine, said muffler cut-out comprising an exhaust chamber provided with an exhaust opening on one side and a fixed sleeve on the other side opposite said opening, a valve stem slidable in said sleeve, a valve attached to said stem and adapted to close said exhaust opening, and a spring for seating said valve, said chamber having a segmental flange adapted to fit such exhaust pipe, said segmental flange having transverse grooves in its opposite ends, and U-shaped clamps adapted to engage said grooves for fastening the cut-off to such exhaust pipe.
- 25 9. As an article of manufacture a muffler cut-out adapted for attachment to the exhaust pipe of an explosive engine, said muffler cut-out comprising an exhaust chamber approximately circular in form and flat at its opposite ends and provided at one end with an exhaust opening and at the other end with a fixed sleeve opposite said opening, a valve stem slidable in said sleeve, a valve attached to said stem and adapted to close said exhaust opening, said chamber
- 35 having a segmental flange adapted to fit such exhaust pipe.
10. A muffler cut-out pipe adapted for use between an explosive engine and a muffler, said pipe having a discharge opening in one side, a chamber surrounding said opening and provided with an outlet to the atmosphere, and a spring operated valve normally closing said outlet, the capacity of the chamber and outlet being sufficient to freely relieve the back pressure on the engine when the valve is open.
- 45 11. A muffler cut-out adapted for application to an engine exhaust pipe between an explosive engine and a muffler, said cut-out comprising an independent chamber adapted for application to the side of said exhaust pipe and being provided with an inlet adapted to register with a discharge opening therein and also with an outlet to the atmosphere, and a spring operated valve normally closing said outlet, the capacity of the chamber and its inlet and its outlet being sufficient to freely relieve the back pressure on the engine when the valve is open.
- 55 12. A relief device for coöperating with the exhaust pipe of an explosion engine comprising a chamber, a relief valve in one side of said chamber, a stem connected to said valve and extending through said chamber, a guide member for said stem outside said chamber, a spring for seating said valve, and means for opening the valve in opposition to the spring.
- 60 75 In witness whereof I have hereunto signed my name this 13th day of January 1908, in the presence of two subscribing witnesses.
